Primary Examiner—Cathy Anne MacCormac
Attorney, Agent, or Firm—Townsend and Townsend and Crew LLP[57] **CLAIM**

The ornamental design for a compact disk holder, as shown and described.

DESCRIPTION

FIG. 1 is a perspective view of a compact disk holder showing our new design;

FIG. 2 is a top plan view thereof;

FIG. 3 is a bottom plan view thereof;

FIG. 4 is a right side elevational view thereof which is rotated 180 degrees;

FIG. 5 is a left side elevational view thereof which is rotated 180 degrees;

FIG. 6 is a rear side elevational view thereof which is rotated 180 degrees;

FIG. 7 is a front side elevational view thereof which is rotated 180 degrees; and,

FIG. 8 is a perspective view of the compact disk holder of FIG. 1 shown in an open configuration.

It is to be understood that the zipper is continuous over the portion indicated by the dot-dash lines in FIGS. 1-7.
